UNITED STATES PATENT OFFICE

153,113

DESIGN FOR A BOTTLE CARRIER

Oliver R. Brekle, Birmingham, Ala., assignor to
M & B Metal Products Company, Birmingham,
Ala., a partnership composed of Milton M.
Magnus and Oliver R. Brekle

Application June 2, 1947, Serial No. 139,402

Term of patent 3½ years

(Cl. D58—4)

To all whom it may concern:

Be it known that I, Oliver R. Brekle, a citizen of the United States of America, residing at Birmingham, county of Jefferson, State of Alabama, have invented a new, original, and ornamental Design for a Bottle Carrier, of which the following is a specification, reference being had to the accompanying drawing, forming a part thereof.

Fig. 1 is an end elevational view of a bottle carrier, showing my new design;

Fig. 2 is a side elevational view;

Fig. 3 is a plan view; and

Fig. 4 is a sectional view taken on line IV—IV of Fig. 3.

What I claim is:
The ornamental design for a bottle carrier, substantially as shown.

OLIVER R. BREKLE.
